TUFTED RUG MACHINE DESIGN CONTROL
MECHANISM

Robert F. Hackney, Otis C. Payne, and William M. Sapp, Jr., Dalton, Ga., assignors to Cabin Crafts, Inc., Dalton, Ga., a corporation of Georgia

Filed Mar. 15, 1956, Ser. No. 571,630

7 Claims. (Cl. 226—9)

This invention relates to a machine for making tufted rugs with variations in the height of pile over the rug surface, some tufts forming the pile being higher than others thereby creating a design or textured appearance in the surface. More particularly, the invention relates to mechanism for causing tufts to be of different heights.

It has been known heretofore to make tufts of different heights in tufted rugs by robbing one tuft of yarn as the succeeding tuft was formed. Various mechanisms have been composed to accomplish that end.

It is an object of the invention to provide a novel, simple mechanism to cause tufts of different heights to be formed by increasing the feed of yarn when tufts of greater heights are desired and by slowing the feed when the tuft height is to be reduced.

Another object is to provide a single driving or feed control member for a plurality of yarn guiding devices or units to cause fast feed of the plurality of yarns individually fed by said units, and at the same time to provide also a single driving member or feed control member for said plurality of yarn guiding devices to cause slower yarn feed, the yarn being shiftable to be acted on by one or the other of the feed control members as selected.

Another object of the invention is to provide shifting means for such yarn guide devices, subject to control of a pattern drum, to cause yarn to be fed fast or slow and to form high or low tufts, as dictated by the pattern.

Another object of the invention is to provide a driving and control mechanism of the foregoing type wherein a single, fast feed member suffices for all yarns and wherein a pair of slow speed members controls the slow feed for alternate yarns.

Other objects and advantages of the invention will become apparent as the invention is described in connection with the accompanying drawings.

In the drawings:

Fig. 1 is a side elevation view partly in section of a portion of a machine embodying the invention.

Fig. 2 is a front elevation broken away illustrating one end of the machine embodying the invention as illustrated in Figure 1.

Fig. 3 is a fragmentary detail view of the pattern drum and associated contact fingers for controlling the solenoid valves employed in the invention.

Fig. 4 is a sectional detail view of tufts formed in a rug by the machine illustrated in Figs. 1-3.

Referring to the drawings, a plurality of the yarns are fed to a plurality of needles which are arranged in a row as is common in tufted rug manufacturing machines. The yarn Y may be caught on a looper after the needle has penetrated the cloth C and may be held during the withdrawal of the needle from the cloth. Since the implements for forming the loops and their operation are well known, no illustration of them is necessary to those skilled in the art.

Although individual yarn ends are fed individually to needles in a bank, the needles are identical and the feeds to alternate needles are identical. Hence, it will be suf-

ficient to illustrate and describe a pair of neighboring yarns and their feeds and control, with the understanding that the feed to the remainder of needles in the bank is duplicated until the desired number of yarn ends and needles are provided.

Journalized in parallel end plates or castings of a machine frame are three vertically aligned rubber covered yarn feed rolls 12, 14 and 16, preferably of equal diameter. The rolls are mounted on shafts 13, 15 and 17 which are driven in any suitable manner by a conventional driving means (not shown). The top and bottom rolls 12 and 16 rotate at the same peripheral speed while the middle roll is driven at a faster peripheral speed, for example approximately two to one when twice as much yarn is used in the high loop as in the low loop. The difference in speed between the fast and slow rolls is subject, however, to variations to suit particular conditions encountered in different machines and also to suit different yarns. Also, the speed of all the rolls may be increased or decreased likewise to suit conditions.

For guiding alternate yarn ends there are provided between the top and middle rolls 12 and 14 and between the middle and bottom rolls 14 and 16, upper and lower horizontal beams 20 and 30. They are laterally offset from one another so that yarn guided by them will be parallel and closely adjacent.

All the upper beams 20 and all the lower beams 30 are pivotally mounted on two horizontal parallel shafts 21, 31, one above the other, running lengthwise of the machine and carried in the end plate of the frame. Thus upper and lower tiers of beams are formed.

On one end of the beams, which preferably is bifurcated, are mounted a pair of vertically spaced parallel horizontal guide wheels 22, 24 and 32, 34 which are rotatably carried on axle pins 23, 25 and 33, 35 laterally extending from the bifurcations or beam arms 26, 26' and 36, 36' respectively.

Extending from the ends of the bifurcated arms 26, 26' and 36, 36' are yarn guide loops 27, 27' and 37, 37', respectively, the loops 27, 27' being vertically aligned and loops 37, 37' likewise being vertically aligned, but their plane being offset from the loops 27, 27'. Extending from the beam 20 at the fork of the arms 26, 26' is a central yarn guide loop 28. A similar yarn guide loop 38 is similarly located on beam 30.

From the foregoing it will be observed that the yarn A may be led down through the guide loop 27 and around the upper yarn guide wheel 22 and then through the middle yarn guide and down and around the lower yarn guide wheel 24 to the lower loop 27'. From the lower loop 27' the yarn A goes to a needle.

In similar manner, the yarn B is fed down through the upper yarn guide loop 37 and around the upper yarn guide wheel 32 and then down through the middle yarn guide loop 38 and around the lower guide wheel 34 to the lower guide loop 37'. From thence it goes through a needle adjacent the needle of the yarn A.

In order to feed the yarns "slow" or "fast" the beams are tilted to cause the wheel 22 to engage the yarn feed roll 12 and the wheel 34 to engage the yarn feed roll 16; or they are tilted to cause the wheel 24 and the wheel 32 to engage the fast speed roll 14.

Tilting of the beams 20 and 30 is accomplished by pneumatic cylinders; and control of their operation is accomplished by solenoid valves which are energized and de-energized by electric circuits which are closed and opened by contact fingers engaging and wiping over a pattern drum.

One end of piston rods 40, 50, respectively, is pivotally connected by pivot pins 29 and 39 respectively to those ends of the beams 20 and 30 which are away from the yarn guide wheels. The other ends of piston rods 40 and

50 connect with pistons 42 moving in cylinders 44 and 54. The pistons and rods are biased by coil compression springs 46 in one end of the cylinders exercising their bias in a direction to oppose the air pressure and urging the yarn guide wheels 24 and 32 against the fast yarn feed roll 14. On admission of air pressure to either one or both of the cylinders, the pistons move and the spring bias is overcome. Thus, the beams are tilted causing one or both wheels 24, 32 to disengage the fast yarn feed roll 14 or one or both wheels 22, 34 to engage the slow yarn feed rolls 12 or 16, respectively.

Control of air to the cylinders is by solenoid valves 60 and 70 of conventional construction having air inlets and exhaust connections 62, 64 and 72, 74, respectively, and a connection 48, 58 respectively to the cylinders 44, 15 54 respectively.

Each beam and its yarn guide wheels together with the pneumatic cylinder and solenoid control valve may be considered as a unit; and each unit is driven selectively by the fast roll 14 or one slow drive roll, the upper units being driven by the slow roll 12 and the lower units being driven by the slow roll 16.

The solenoids are connected in series to a source of electric power (not shown) and to switch fingers 66 and 76, respectively. The switch fingers may be flexible sheet metal strips which are good electrical conductors. The fingers for the series of solenoids which control the series of pneumatic cylinders and pistons, and in turn the beam and yarn feed, are arranged in a row and mounted on an insulated supporting bar 84 over a pattern drum 80 so as to engage and wipe over the surface thereof. The drum is of conducting material and connected in the power circuit. A pattern 82 of non-conducting sheet material is adhered to the surface of the drum so that the circuit is broken when the pattern comes under a finger. Thus, the solenoid and cylinder controlled by that finger is deactivated and the spring 46 (for example) moves the beam 20 to engage the yarn guide wheel 22 with the slow yarn feed roll 12 and disengage the wheel 24 from the fast yarn feed roll 14.

When the switch finger again comes in contact with the surface of the drum at a conducting area after the portion of the pattern has passed from under the switch finger, the circuit will again be completed to energize the solenoid valve and admit air to the pneumatic cylinder whereupon causing the beam, for example the beam 20, to be moved to overcome the biasing pressure of the spring 46 whereupon the yarn guide wheel 22 will come in contact with the slow yarn feed control roll 12 causing the yarn A to be fed at a slower speed.

When operating a machine constructed as described above, the bank of needles descends and penetrates the cloth C. Conventionally, the yarn loop, which each needle carries down through the cloth, is caught and held by a looper (not shown) as the needle ascends, forming a tuft of predetermined height. On the next reciprocation of the needle, the process is repeated forming another tuft of the same height—unless the slow yarn feed roll is being engaged by the yarn guide wheel. In the latter event, insufficient yarn is fed to form a normal loop, in consequence of which the descending needle robs yarn from the previously formed tuft, lowering its height, in order to have enough yarn to form the new tuft.

From the foregoing it will be observed that by feeding the yarn slower or faster the tufts formed in the rug will be of different heights and thereby a design will be formed in the surface of the rug. Whether the design is indented into the surface or is raised above the surface of the rug, in other words whether the design appears to be carved into or to be embossed upon the rug, will depend on how the pattern design is applied to the drum.

From the foregoing it will also be observed that by having a single fast yarn-feed-control roll all of the yarns can be controlled selectively to have their feed increased from that one driving or yarn-feed-control roll. It will

be obvious that it may not be necessary to have two slow yarn-feed-control rolls, but that for economy of space it may be desirable in many, if not in most cases, to employ two slow speed rolls.

Many modifications within the scope of the invention will occur to those skilled in the art. Therefore the invention is not limited to the specific form and configuration illustrated:

What is claimed is:

1. In a tufted rug making machine having means for producing a design by formation of high and low pile tufting and including a bank of reciprocating needles for carrying yarn through a cloth backing to form loops, a feed means for the yarn comprising a plurality of rotating power-driven parallel yarn feed rolls one of which is rotated faster than the remainder, a plurality of individual units each adapted to guide and control the feed of yarn; said units being located side by side in two rows one above the other, and each unit comprising two rotatable yarn guide wheels simultaneously shiftable to engage and be rotated by either said fast or a slow feed roll selectively, pivotally mounted shifting means on which said yarn guide wheels are mounted, and selecting means including a pneumatic cylinder having a piston therein and a solenoid valve controlling admission of air to and discharge of air from said cylinder to selectively operate each shifting means individually, one fast and one slow yarn feed roll serving a row of said units.

2. In a tufted rug making machine having means for producing a design by formation of high and low pile tufting and including a bank of reciprocating needles each carrying yarn through a cloth backing to form loops, a feed means for the yarn comprising a plurality of rotating power-driven yarn feed rolls one of which is rotated faster than the remainder, a plurality of individual units each adapted to guide and control the feed of yarn, said units being located side by side in a row, each unit comprising a shiftable support, rotatable yarn guide means on said support adapted to engage and be rotated by either said fast or slow feed roll, means including a pneumatic cylinder having a piston therein and a solenoid valve controlling admission of air to and discharge of air from the cylinder to shift each support individually to accomplish said alternate engagement in consequence of which the height of a tuft is reduced when the slower feed roll is engaged, one fast and one slow yarn-feed roll serving a row of said units.

3. In a tufted rug making machine as claimed in claim 2 having selecting means including a pattern on a moving surface having the design desired to appear in the rug, electrical means responsive to design variations in the pattern on said moving surface to operate said shiftable support to cause the design to appear in the rug.

4. In a tufted rug making machine having means for producing a design by formation of high and low pile tufting and including a plurality of reciprocating needles for carrying yarn through a cloth backing to form loops, a feed means for the yarn comprising a plurality of rotating power-driven parallel yarn feed rolls one of which is rotated faster than the remainder, a plurality of units to guide and control the feed of yarn; said units being located side by side in two rows one above the other, and each unit comprising two rotatable yarn guide wheels simultaneously shiftable to engage and be rotated by either said fast or a slow feed roll selectively, pivotally mounted shifting means on which said yarn guide wheels are mounted; and selecting means including a pneumatic cylinder having a piston therein and a solenoid valve controlling admission of air to and discharge of air from said cylinder to operate said shifting means, one fast and one slow yarn feed roll serving a row of said units; said selecting means including a pattern having electrically conductive and non-conductive portions laid out on a moving surface having the design desired to appear in the rug, electromagnetically responsive means to cause

operation of the shifting means for said units individually, and electric switching means operated by the pattern on said moving surface to control said individually electromagnetically responsive means.

5. In a tufted rug making machine having means for producing a design by formation of high and low pile tufting and including a plurality of reciprocating needles for carrying yarn through a cloth backing to form loops, a feed means for the yarn comprising a plurality of rotating power-driven yarn feed rolls one of which is rotated faster than the remainder, a plurality of units to guide and control the feed of yarn, said units being located side by side in a row, each unit comprising a shiftable support, rotatable yarn guide means on said support adapted to engage and be rotated by either said fast or slow feed roll, means including a pneumatic cylinder having a piston therein and a solenoid valve controlling admission of air to and discharge of air from the cylinder to shift said support to accomplish said alternate engagement in consequence of which the height of a tuft is reduced when the slower feed roll is engaged, one fast and one slow yarn-feed roll serving a row of said units; and selecting means including a pattern having electrically conductive and non-conductive portions laid out on a moving surface having the design desired to appear in the rug, electromagnetically responsive means to cause operation of the shiftable support for said units individually, and electric switching means operated by the pattern on said moving surface to control said individually electromagnetically responsive means.

6. In a tufted rug making machine having means for producing a design by formation of high and low pile tufting and including a plurality of reciprocating needles for carrying yarn through a cloth backing to form loops, a feed means for the yarn comprising a plurality of rotating power-driven yarn feed rolls one of which is rotated faster than the remainder; a plurality of units to guide and control the feed of yarn, said units being located side by side in a row, each unit comprising rotatable yarn guide means shiftable to engage and be rotated by either said fast or a slow feed roll selectively, shifting means to cause said selective engagement; and selecting means to operate said shifting means, one fast and one

slow yarn feed roll serving a row of said units, said selecting means including a pattern having electrically conductive and non-conductive portions laid out on a moving surface having the design desired to appear in the rug, electromagnetically responsive means to cause operation of the shifting means for said units individually, and electric switching means operated by the pattern on said moving surface to control said individually electromagnetically responsive means.

5 7. In a tufted rug making machine having means for producing a design by formation of high and low pile tufting and including a plurality of reciprocating needles for carrying yarn through a cloth backing to form loops, a feed means for the yarn comprising a plurality of rotating power-driven yarn feed rolls one of which is rotated faster than the remainder, a plurality of units to guide and control the feed of yarn, said units being located side by side in a row, each unit comprising a shiftable support, rotatable yarn guide means on said support adapted to engage and be rotated by either said fast or slow feed roll, means to shift said support to accomplish said alternate engagement in consequence of which the height of a tuft is reduced when the slower feed roll is engaged, one fast and one slow yarn-feed roll serving a row of said units; and selecting means including a pattern having electrically conductive and non-conductive portions laid out on a moving surface having the design desired to appear in the rug, electromagnetically responsive means to cause operation of the shifting means for said units individually, and electric switching means operated by the pattern on said moving surface to control said individually electromagnetically responsive means.
